UNITED STATES PATENT OFFICE

1,979,502

TARGET TRAP

Willis J. Sutcliffe, Waterloo, Iowa

Application January 25, 1933, Serial No. 653,381

1 Claim. (Cl. 124—3)

My invention relates to improvements in target traps for marksmen, and the object of my improvement is to provide means in such a device as will permit its target carrying frame and members to be adjustably tilted and secured laterally as additional to the usual means for tilting it adjustably longitudinally, and whereby the operation is perfected in increasing the latitude of variations in directing targets in unforeseen 10 directions.

This object I have accomplished by the means which are hereinafter described and claimed, and which are illustrated in the accompanying drawing, it being understood that various modifications 15 in the details of construction and arrangement of parts of the improvement and its connections may be made without departure from the principle and scope of the invention as defined in the following claim.

20 In said drawing, Fig. 1 is a side elevation of a target trap of a well known construction, containing my improvement, and with parts sectioned or broken away. Fig. 2 is an enlarged detail perspective view of the specific laterally 25 tiltable joint of my invention, as combined with the longitudinally tiltable joint of such an apparatus as disclosed in Fig. 1.

The numeral 1 denotes a plank upon which a metallic base block 2 may be mounted, the latter 30 having an upwardly opening socket to receive the depending shaft 4 of a rock-body 3. The latter has at opposite ends holes to receive therethrough respectively pintle-bolts 5 and 6 carrying terminal securing nuts.

35 The numeral 12 denotes the U-shaped frame of the target carrying mechanisms having on its lower member at or near one end longitudinally spaced projections 16 and 13 both apertured in alinement at their tops to receive the end parts of 40 a fixed rod or bearing shaft 11. Another rock-body 8 has at its top spaced lugs 9 and 10 also apertured in alinement with their apertures traversed loosely by the shaft 11, which provides a laterally adjustable hinged connection permitting 45 lateral rocking adjustments to the frame 12 as desired, and to be secured in any such adjustments as follows.

The pintle-bolt 5 traverses a hole in the rock body 8 and serves as a pivot or hinge therefor 50 for longitudinally tilting, the body 8 having an arcuate slot 7 traversed by said pintle-bolt 6 whose end nut permits the body 8 to be secured in an adjusted position longitudinally together with the superincumbent frame 12.

55 As shown in said Fig. 2 the fixed projection 13 on the frame 12 is also a depending member having its lower end widened with an arcuate slot 15 traversed by an end part of a threaded stem 14 fixed in the abutting end wall of the rock-body 8, and secured by an end nut, when the

frame 12 has been laterally tilted to a desired degree on the hinge shaft 11.

The mechanism mounted on the frame 12 has not been specifically described, being conventionally represented as adapted for imparting rock- 65 ing movement of a rock-shaft 17 which has a target carrying arm or member 18 functioning in the usual manner.

The combination of my additional laterally 70 tiltable hinge means at 11 between the rock-body 8 and the frame 12, permits both the tilting of the frame 12 and with it the target carrying arm 18, whereby the planar part of the arm which supports a target is more or less inclined laterally. This changed inclination of the target 75 carrier allows it to discharge the target at different levels relative to the earth, whereby an additional variation is introduced into the fortuitous or unforeseen delivery of the target, simulating more closely than in other devices the 80 varying flight of a bird in direction above the ground as well as in unforeseen direction in a horizontal plane away from the apparatus. The two adjustments thus afforded for the frame and its carrier 18 perfect the function of the same 85 from the standpoint of a marksman, who desires opportunity for the utmost exercise of his skill as shown in entirely unforeseen emergencies.

Having described by invention, what I claim as new, and desire to secure by Letters Patent, is: 90

In a target carrying and delivering apparatus, in combination, a relatively fixed body having a vertically hollowed seat, a horizontally rockable basal support having a depending central spindle mounted in said seat, a U-shaped frame spaced 95 above said basal support and having on its lower member a transversely arranged fixed hanger provided with an arcuate transverse slot in its lower part, the upper portion of said basal support being vertically flattened diametrically, the 100 lower member of said U-shaped frame having a part adjacent to said hanger diminished to be a pintle, a plate longitudinally apertured at its upper end to be dependently swingingly hung on said pintle, the forward edge of said plate 105 having a fixed and threaded pin therein traversing the slot in said hanger, means on said pin for adjustably securing the hanger to said plate to permit said frame to swing laterally adjustably, the rear end of said plate having a pivotal connection to the flattened part of said basal support to permit the plate and said frame to swing vertically thereon, the forward part of said plate having a slot curved radially relative to said pivotal connection, a bolt loosely traversing 110 said plate and the said latter slot, and fastening means adjustably mounted on said bolt to secure the plate on the basal support in a desired position of upwardly tilted adjustment.
